TIRE

Robert G. Smith, Birmingham, Mich., assignor to United States Rubber Company, New York, N. Y., a corporation of New Jersey

Application April 5, 1956, Serial No. 40,924

Term of patent 14 years

(Cl. D90—20)

Fig. 1

Fig. 2

Fig. 3

*Fig. 4*Fig. 1 is a side elevational view of a tire showing my new design.

Fig. 2 is an enlarged sectional and fragmentary perspective view of the sidewall of the tire shown in Fig. 1.

Fig. 3 is a detail sectional view taken substantially on the plane indicated by line III—III of Fig. 2, and

Fig. 4 is a perspective fragmentary sectional view of Fig. 1.

The characteristic features of the design reside in a tire having a sidewall provided with a circumferentially extending rib, and circumferentially spaced, generally radially extending recesses in said rib of a color different

from that of an adjacent portion of the sidewall, substantially as shown in full lines on the drawings.

I claim:

The ornamental design for a tire, substantially as shown and described.
